[57] CLAIM

The ornamental design for an escargot container, as shown and described.

DESCRIPTION

FIG. 1 is a top, left side perspective view of an escargot container of the present design, which escargot container has been shown in use with multiple escargot containers in the form of a serving platter, only one escargot container being shown in solid line, the other escargot containers of the serving platter being shown in broken line forming no part of the design of the individual escargot container, the platter design is shown for purposes of illustrating the environment in which multiple escargot containers are used;

FIG. 2 is an enlarged view of the individual escargot container as shown in FIG. 1;

FIG. 3 is a top plan view thereof, a bottom plan view is not shown as it forms no part of the design;

FIG. 4 is a front elevational view of the thereof;

FIG. 5 is a right side elevational view of thereof;

FIG. 6 is a rear elevational view thereof; and,

FIG. 7 is a left side elevational view thereof.
